UNITED STATES PATENT OFFICE.

SEBASTIAN ZIANI DE FERRANTI, OF GRINDLEFORD, NEAR SHEFFIELD, ENGLAND.

TURBINE.

No. 901,981.

Specification of Letters Patent.

Patented Oct. 20, 1908.

Original application filed October 31, 1903, Serial No. 179,407. Divided and this application filed September 16, 1907.
Serial No. 393,125.

To all whom it may concern:

Be it known that I, SEBASTIAN ZIANI DE FERRANTI, a subject of the King of Great Britain and Ireland, and residing at Grindleford, near Sheffield, in the county of Derby, England, have invented certain new and useful Improvements in and Relating to Turbines, of which the following is a specification.

10 The present invention relates to turbines of the type described in my patent application, Serial No. 179,407, from which the present application is divided.

In turbines of the type in question, the 15 working fluid is expanded in a number of stages with intermediate re-heating so that the expansion on the whole may be substantially isothermal.

The present invention consists in super- 20 heating the fluid prior to its isothermal expansion in the turbine so that on the one hand a higher thermal efficiency may be obtained and on the other hand a higher mechanical efficiency owing to the use of dry fluid only 25 in the turbine and a consequent large reduction in the fluid friction. These advantages will be more clearly understood by comparison with Figure 16 of the accompanying drawings. This Fig. No. 16 shows an en- 30 tropy - temperature diagram of the cycle through which the fluid passes when no initial superheating is provided. In this figure, the steam (taking steam by way of example of a suitable working fluid) when de- 35 livered to the turbine will be to a certain extent wet as in ordinary practice, its state being represented by the point E. After adiabatic expansion in the first stage of the turbine, the steam is in the state F and is still 40 necessarily wet. The heat received in the first re-heater first dries the working fluid, its temperature remaining constant along the line F G, and subsequently superheats to say the boiler temperature. Further adiabatic 45 expansions G H and re-heats H G then take place as shown in the diagram. The disadvantages of such a cycle are that the heat taken in along the line F G in particular is imparted to the fluid at a comparatively low tem- 50 perature and is consequently in accordance with well-known principles inefficiently converted into work while even in subsequent re-heats, the temperature throughout is below the highest. Hence the thermal efficiency of

the cycle due to the re-heating is probably not 55 substantially altered. The mechanical efficiency is, however, improved since, after the first expansion, the steam is dry and hence the fluid friction due to wet steam is absent. All these disadvantages are overcome, how- 60 ever, by initial superheating of the steam as shown in the illustrative examples given in Figs. 12 to 15. In such cycles it will be seen that the steam is dry throughout its whole ex- 65 pansion in the turbine, fluid friction being thereby reduced to a minimum, while the heat taken in by the fluid from the re-heaters is taken in at a high temperature and is therefore very efficiently converted. To sum up, therefore, both the mechanical and 70 thermal efficiencies of the turbine are increased by initial superheating of the steam.

Referring to the accompanying drawings, Fig. 1 shows the general arrangement in elevation of a complete installation of plant 75 having fire-heated superheaters and re-heaters, Figs. 2, 3 and 4 being corresponding sections on the lines X X, Y Y and Z Z re- 80 spectively of Fig. 1. Fig. 5 shows a modification of the arrangement of Fig. 1, and Fig. 6 an arrangement adapted to the case of a Lancashire or other flue boiler. Fig. 7 shows another general arrangement in which superheated steam is employed in the re- 85 heaters; Fig. 8 is a detail view showing an al- 90 ternative arrangement of the re-heater coils; Fig. 9 is a modification of the arrangement of the re-heaters of Fig. 7, while Figs. 10 and 11 show diagrammatically other methods of reheating by means of superheated steam. 95 Figs. 12 to 15 are sketches of entropy-tem- 100 perature diagrams showing examples of va- 105 rious operative cycles according to the present invention, Fig. 16 being an explanatory diagram.

I will describe my invention as applied to one modification in what I consider its best form, viz., with all the elements combined together in one machine so as to obtain the highest economy. I will assume the turbine 100 is to use steam as the medium of expansion and that it is desired to employ a compound turbine of the impact type, although it will be seen that any condensable elastic fluid may be used and that a compound turbine of 105 any of the other well known types may be employed. I therefore construct (Figs. 1 to 4) a compound or multiple stage impact

steam turbine *a* in a well known manner but I separate each stage in such a way that I can pass the steam exhausting from the first stage through a reheater delivering into the inlet of the second stage and from its exhaust to a second reheater and so on, re-heating after each stage expansion to the final exhaust. I arrange the turbine *a*, on a horizontal shaft and provide the re-heaters below the turbine body. These re-heaters, *d c* are tube elements situated in a combustion flue, *d*, which also contains the boiler, *e f*, superheater, *h i*, and water heater *k l*, elements.

In connection with the exhaust passage, *m*, of the turbine, I arrange a coil regenerator, *n*, so as to extract the heat from the exhaust which comes from the turbine at a temperature approaching the maximum temperature of the cycle; I arrange the water supply to the inlet of this regenerator to come from the condenser *u* or from the hot well by way of the pipe *o*, and I connect the regenerator outlet *p* which is nearest to the turbine, preferably to the water heater element, by way of the pipe *r* so that the heat of the turbine exhaust is in part restored to the working fluid.

I find it convenient to employ boiler, *e f* and superheater elements *h i* of a similar character, which may take the form of upper and lower drums, joined by a large number of nearly vertical tubes, which traverse the flue *d*, and therefore baffle the combustion gases. The boiler, superheater, reheater and water heater elements are all arranged in the flue, *d*, in such a way as to obtain the best extraction of heat from the gases of combustion, which are produced and burned from one end of the furnace. I may also employ coal-dust as the furnace combustible.

Beneath or around the furnace flue, carrying the boiler, superheater, reheater and water heater elements, I prefer to construct flues to carry the products of combustion to the chimney *s* and through these waste gas flues I carry iron air ducts *t*, which convey the air supply to the furnace in a direction preferably counter to the flow of the waste gases, thus forming an air regenerator and obtaining hot air for the fuel combustion.

According to a modification as shown in Fig. 5 the length of piping between the turbine and re-heaters is reduced to a minimum, the regenerator being removed from the position shown in Fig. 1 and placed beyond the flue heated elements. Fig. 5 also shows another form of reheater consisting in one or more heaters from which tubes depend. Fig. 6 shows an arrangement of parts in which a Lancashire or other flue boiler is used instead of the water tube boilers of Fig. 1. The same letters are used in the last two figures as in Fig. 1 to denote similar parts.

According to another modification shown in Figs. 7, 8 and 9 instead of direct fire heat-

ing of the re-heaters, I arrange them to be heated indirectly by superheated steam. Thus in Fig. 7, the steam generator is shown at 2, provided with steam-drums 3, from which the steam is led through the superheater 4, in the uptake. After superheating, the steam divides into two parts one part going direct to the turbine, 5, by way of the pipe 6, and the other part passing to the re-heaters 7, by way of the pipe 8. In this example shown the turbine is provided with five re-heaters, the superheated steam from the pipe 8, passing through them in parallel. A pump 9, is provided to return the condensed steam issuing through the pipe 25, from the re-heaters to the boiler through the pipe, 10, feed water heater 26 and pipe 27. The arrangement I prefer in the re-heaters is to conduct the steam from the turbine after the first stage of expansion through the pipe 11, to the bottom of the first re-heater and then upwards in a direction counter to that of the superheated steam through the coil 12, and back to the turbine. This action is repeated after each stage of expansion in the turbine, the steam finally passing through the exhaust pipe, 13, to the regenerator, 14. It will be understood that as the figure is merely diagrammatic, the proportions of re-heater coils, and the other parts are not those which would be adopted in practice.

An alternative arrangement of the re-heater coils is shown in Fig. 8, steam from the turbine being led to the bottom of the re-heater through the pipe 15, whence it returns through the pipe 16, meanwhile traveling in an opposite direction to that of the superheated steam which enters the top of the re-heater through the pipe 17, and flows through the coil 18, to its outlet after which its path back to the boiler is as before.

Referring again to Fig. 7, the steam from the turbine passes through the regenerator to the condenser 19, which may be of the jet condensing type, supplied with cooling water through the pipe 20, and provided with an air pump 21. Another pump, 22, which may if convenient, be worked off the air pump, 21, serves to pass a part of the outflow from the condenser through the regenerator coils, 28, whence it passes on and joins the condensed steam from the re-heaters. The combined steam may then be pumped through the economizer or feed water heater, 26, placed in the uptake and returned to the boiler, thus completing the cycle.

In Fig. 8, is shown another arrangement of the re-heaters; the coils 12, through which the steam from the turbine passes, are in this case arranged in one large compartment, 24, superheated steam entering through the pipe, 8, as before and leaving after condensation, by the pipe, 25, after which its course is as described above.

Instead of dividing the superheated steam

into two parts according to the methods of Figs. 7 and 9 I may use the following system. Steam from the generator 2, (see Fig. 10) is led through the pipe, 29, to the superheater 30; after being superheated in the coils 31, it passes through the pipe 32, direct to the re-heaters 33, which are in this case, preferably of the type shown in Fig. 8. The steam then returns through the pipe 34, to the superheater, when it is re-superheated by passing through the coils 35, 36, after which it goes direct to the turbine by way of the pipe 37.

In Fig. 11, I have shown yet another method of conducting the superheated steam through the re-heaters. Steam from the generator 2, passes as before, through the pipe 29, to the coils 31, of the superheater 30; it then passes through the pipe 38, to the re-heaters 39. These are of the same general type as those shown in Fig. 8, except that the coils are divided into upper and lower sets. The steam after passing through the upper coils, 40, 40, of the re-heaters returns through the pipe 41, to the coils 35, 36, of the superheater and after issuing thence divides into two parts, the one part passing through the pipe, 42, to the turbine and the other part by way of the pipe 43, through the lower coils 44, 44, of the re-heaters, the water of condensation being returned by the pump, 45, to the generator, either directly through the pipe, 46, or indirectly through a feed water heater such as is shown at 26, Fig. 7.

With regard to the turbine itself, as above mentioned, it is of the compound or multiple stage expansion impact type. Each stage of the expansion thus forms a turbine of what is known as the Laval type. Each pair of fixed and moving elements of this turbine also constitutes a complete turbine in which the drop of pressure is arranged to take place in the jets of the fixed element only. The jet chamber of the second stage is supplied through the first re-heater, and here again the drop of pressure takes place in the fixed jets of the second stage, and so on through the various stages of expansion in the turbine down to the exhaust.

It will be seen that by means of the re-heaters provided at each stage of expansion, the temperature of the turbine is maintained practically uniform from end to end, and the exhaust steam will pass from the turbine practically at the temperature at which it at each stage passes to the re-heater, the larger the number of stages employed the nearer being the approach to isothermal expansion. The exhaust steam then delivers through a passage, in which is situated the regenerator for the extraction of its heat, and then into the condenser, which is preferably a jet or ejector condenser employing practically air freed water.

It will be seen that various elements of my

complete isothermal expansion power generator may be omitted without departing from my invention, although of course, the omission of these elements will involve a less economical production of power. For example:—

(a) The regenerator may be omitted and in this case the isothermal expansion is only carried over a portion of the range the remainder of the expansion being effected adiabatically; reheating should, however, be carried to such a stage as to insure a slightly superheat exhaust. I find it possible to secure a considerable gain in economy by the use of only three reheating stages, the steam from the last of these being preferably expanded adiabatically and passed through the regenerator.

(b) It will be obvious that the air regenerator may be omitted and also the condenser although such omissions will involve a smaller advantage.

It will be seen that an isothermal expansion turbine of my new type has to work under the maximum temperature of the cycle. This has the disadvantage that lubrication is rendered more difficult. It has, however, several great advantages. One of these is that the steam can be maintained practically dry throughout the whole range of expansion. This fact has great influence in reducing the frictional losses in the turbine. Again no great variations of temperature exist in the turbine, the whole turbine casing being practically maintained at the same temperature. The difficulties ordinarily occurring in steam turbines through unequal expansion due to unequal heating of the different parts of the turbine practically disappear.

Although I have used the term "isothermal expansion" in setting forth my invention I am, nevertheless aware that the expansion through each stage is actually closely adiabatic. The effect of the re-heaters taken in conjunction with the adiabatic expansion, is however, to cause the resultant expansion line to cross and re-cross an isothermal line drawn at about the mean temperature of the re-heats, said expansion line thus approximating to such an isothermal line more or less closely according to the number of re-heats and it is in this sense that I wish the words "isothermal expansion" to be construed, both in the body of the specification and in the following claims.

It will be seen that many modifications can be made in the details of the cycles employed without departing from the essence of my invention and in order to explain more fully the sense in which I use the term "isothermal expansion," reference is made to Figs. 12 to 15 of this specification, though I wish it to be clear that the cycles, temperatures and other details shown in these fig.

ures are merely given by way of illustrative examples and I do not wish in any way to be restricted to the particular details shown.

The entropy-temperature diagrams constituting the Figs. 12 to 15 are practically self-explanatory, the expansions in the different turbine stages being in each case represented by the substantially adiabatic lines, A B, while the intermediate re-heats are shown by the lines, B A. The figures at the various points of the diagram are by way of example of the temperatures existing at these points in degrees centigrade. It will be seen that in each example given the resultant expansion line continually crosses and re-crosses the dotted isothermal line, C D, which is drawn at about the mean temperature of the re-heats.

Having now described my invention, what I claim as new and desire to secure by Letters Patent is:—

1. In combination with a plurality of elastic fluid motors wherein said fluid undergoes progressive expansions, means for initially superheating said fluid together with means for maintaining the temperature of said fluid at the inlets of the second and following motors equal to the temperature of superheat at the inlet of the first of said motors.
2. In combination with a plurality of elastic fluid motors wherein said fluid undergoes progressive expansions, means for initially superheating said fluid together with means for maintaining the temperature of said fluid at the inlets of the second and following motors equal to the temperature of superheat at the inlet of the first of said motors, together with a regenerator through which the exhaust fluid is passed.
3. In combination with a plurality of elastic fluid motors, wherein said fluid undergoes progressive expansions, means for initially superheating the fluid together with means disposed between successive expansions for re-heating said fluid, the mean temperatures of the re-heats being substantially identical.
4. In combination with a plurality of elastic fluid motors wherein said fluid undergoes progressive expansion, means for superheating the fluid at some point of the total expansion, together with means disposed between successive expansions after said superheating point for re-heating said fluid at each re-heat to the superheating temperature.
5. In combination with a plurality of elastic fluid motors, wherein said fluid undergoes progressive expansions, means for superheating the fluid at some point of the total expansion together with means disposed between successive expansions after said superheating point for heating said fluid to a uniform high temperature.
6. In combination with a plurality of elastic fluid motors, wherein said fluid undergoes

progressive expansions, means for superheating the fluid at some point of the total expansion together with means disposed between successive expansions after said superheating point for heating said fluid at each re-heat to such an extent that the next expansion is not sufficient to bring said fluid to the saturated condition, the mean temperatures of the re-heats being substantially identical.

7. In combination with a plurality of elastic fluid motors, wherein said fluid undergoes progressive expansions, means for initially superheating said fluid; means for expanding said superheated fluid adiabatically in said motors and means disposed between said adiabatic expansions for re-heating said fluid to the temperature of superheat at each re-heat.

8. In combination with a plurality of elastic fluid motors, wherein said fluid undergoes progressive expansions, means for initially superheating said fluid; means for expanding said superheated fluid adiabatically in said motors and means disposed between said adiabatic expansions for re-heating said fluid so as to render the expansion on the whole substantially isothermal.

9. In combination with a plurality of elastic fluid motors, wherein said fluid undergoes progressive expansions, means for initially superheating said fluid; means disposed between said expansions for reheating the fluid so as to render the expansion on the whole substantially isothermal together with a regenerator through which the exhaust fluid passes.

10. In combination with a plurality of elastic fluid motors, wherein said fluid undergoes progressive expansions, means for superheating the fluid at some point of the total expansion; means disposed between successive expansions after said superheating point for heating said fluid at each re-heat to such an extent that the next expansion is not sufficient to bring said fluid to the saturated condition, the mean temperatures of the re-heats being substantially identical, together with a regenerator through which the exhaust fluid passes.

11. In combination, a plurality of turbine chambers; superheating means connected to the inlet of one of said chambers; combustion means for generating hot gases; re-heaters operatively connected between certain of said chambers, said re-heaters being disposed in the path of said hot gases to abstract a proportion of the heat of the same together with means for abstracting a further proportion of said heat.

12. In combination a plurality of turbine chambers, flue means for conducting hot gases; superheater, reheat, elastic fluid regenerator and feed water heater elements

disposed within said flue means and ducts operatively connecting said elements and said turbine chambers.

13. In combination a plurality of turbine chambers; flue means for conducting hot gases; superheater and re-heater elements disposed within said flue means, said elements abstracting a proportion of the heat of said gases; ducts operatively connecting 10 said elements and said turbine chambers and means other than said superheater and re-heater elements for abstracting a further proportion of the heat of said gases.

14. The combination of a plurality of elastic fluid turbine wheels; a shaft supporting the same; a casing; partitions in said casing forming successive wheel chambers; means for superheating elastic fluid and a connection therefrom to the first of said chambers; 20 conduits external to said casing and connecting said chambers in series together with means for heating said conduits.

15. The combination of a plurality of elastic fluid turbine wheels; a shaft supporting the same; a casing; partitions in said casing forming successive wheel chambers; means for superheating elastic fluid and a connection therefrom to the first of said chambers; 25

conduits external to said casing and connecting said chambers in series together with a 30 duct for conveying heated gas, the said connecting conduits extending into said duct.

16. A turbine divided into stages; a furnace flue; superheater reheat and generator elements operatively disposed within 35 said flue, substantially as and for the purpose described.

17. A turbine divided into stages, a furnace flue; superheater, reheat generator and feed water elements operatively disposed within said flue, substantially as and for the purpose described.

18. A turbine divided into stages; a furnace flue; superheater and reheat elements operatively disposed within said flue substantially as and for the purpose described 45 and abstracting a proportion of the heat in the flue gases and means for extracting a further proportion of said heat.

In testimony whereof I affix my signature 50 in presence of two witnesses.

SEBASTIAN ZIANI DE FERRANTI.
